(57) **CLAIM**

The ornamental design for a drying rack and mat, as shown and described.

DESCRIPTION

FIG. 1 is a front perspective view of a drying rack and mat according to the present invention;

FIG. 2 is a front perspective view of the drying rack and mat shown in FIG. 1, but with environmental portions removed for purpose of clarity;

FIG. 3 is a front view thereof;

FIG. 4 is a rear view thereof;

FIG. 5 is a left-side view thereof, the right-side view being a mirror image thereof;

FIG. 6 is a top view thereof;

FIG. 7 is a bottom view thereof; and

FIG. 8 is a cross-sectional view taken on line 8-8 of FIG. 6.

FIG. 9 is a front perspective view of the drying rack and mat shown in FIG. 1, but with the mat shown in a closed position, illustrating an alternative configuration of the present invention;

FIG. 10 is a front view of the drying rack and mat shown in FIG. 9;

FIG. 11 is a rear view thereof; and

FIG. 12 is a left-side view thereof.

FIG. 13 is a front perspective view of an alternative embodiment of the present invention;

FIG. 14 is an enlarged perspective view from FIG. 13, but with environmental portions removed for purpose of clarity;

FIG. 15 is a front view thereof;

FIG. 16 is a rear view thereof;

FIG. 17 is a left-side view thereof, the right-side view being a mirror image thereof; and,

FIG. 18 is a top view thereof.

Any elements shown in dashed lines or broken lines form no part of the claimed invention in this application, and are instead included to show environmental aspects of the claimed invention. Also, the broken lines shown adjacent to any shaded portions form an unclaimed boundary of the design.
